(57) **CLAIM**

The ornamental design for a wireless charger, as shown and described.

DESCRIPTION

FIG. 1 is a front, right and top perspective view of a wireless charger showing my new design;

FIG. 2 is a rear, left and top perspective view thereof;

FIG. 3 is a rear, left and bottom perspective view thereof;

FIG. 4 is a front view thereof;

FIG. 5 is a rear view thereof;

FIG. 6 is a left view thereof;

FIG. 7 is a right view thereof;

FIG. 8 is a top view thereof;

FIG. 9 is a bottom view thereof;

FIG. 10 is a perspective view, showing the foldable part in a closed position; and,

FIG. 11 is an enlarged rear view thereof, shown in the selected portion in FIG. 5.

The broken line portion of the drawings illustrate features of the wireless charger that form no part of the claimed design.
